(57) **CLAIM**

The ornamental design for a backhoe, as shown and described.

DESCRIPTION

FIG. 1 is a front elevation view of a backhoe, showing our new design;

FIG. 2 is a rear elevation view thereof;

FIG. 3 is a left side elevation view thereof;

FIG. 4 is a right side elevation view thereof;

FIG. 5 is a top view thereof;

FIG. 6 is an enlarged top view of a portion thereof showing an inside of the cabin, with the top of the cabin removed for convenience;

FIG. 7 is an enlarged upper rear perspective view of a portion thereof showing the inside of the cabin, with the top of the cabin removed for convenience;

FIG. 8 is an enlarged rear elevation view of a portion thereof showing the inside of the cabin, with the rear side of the cabin removed for convenience;

FIG. 9 is a further enlarged top view of a portion thereof showing the inside of the cabin, with the top of the cabin removed for convenience; and,

FIG. 10 is a further enlarged upper rear perspective view of a portion thereof showing the inside of the cabin, with the top of the cabin removed for convenience.

A bottom view is omitted because it is plain and unornamental and forms no part of the subject matter of the claimed design.

The portions of the backhoe shown in broken lines in FIGS. 1-10 form no part of the claimed design.
